CLAIM

The ornamental design of a dimmer controller as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever. FIG. 1 is a top front right perspective of a dimmer controller; FIG. 2 is a bottom rear left perspective thereof; FIG. 3 is a right side elevation thereof; FIG. 4 is a left side elevation thereof; FIG. 5 is a front elevation thereof; FIG. 6 is a rear elevation thereof; FIG. 7 is a top plan view thereof; and, FIG. 8 is a bottom plan view thereof. The broken lines in the drawings illustrate portions of the dimmer controller that form no part of the claimed design.
